(57) **CLAIM**

The ornamental design for a liquid dispenser and purifier, as shown and described.

DESCRIPTION

FIG. 1 is a perspective view of a liquid dispenser and purifier showing our new design;

FIG. 2 is a bottom perspective view thereof;

FIG. 3 is a rear perspective view thereof;

FIG. 4 is a front view thereof;

FIG. 5 is a rear view thereof;

FIG. 6 is a left side view thereof;

FIG. 7 is a right side view thereof;

FIG. 8 is a top plan view thereof;

FIG. 9 is a bottom plan view thereof;

FIG. 10 is a perspective view thereof with the tray in an alternate position; and,

FIG. 11 is a perspective view thereof with the tray removed for ease of illustration.

The parts shown in dashed lines form no part of the claimed design.

The broken lines in the drawing depict environmental subject matter only and form no part of the claimed design.

The broken lines in the drawing depict portions of the liquid dispenser and purifier that form no part of the claimed design.

1 Claim, 11 Drawing Sheets
